SHIPPING CONTAINER AND CARRIER

Frank A. Marx, Cincinnati, Ohio, assignor to The Richardson Taylor-Globe Corporation, Cincinnati, Ohio, a corporation of Ohio

Application March 16, 1937, Serial No. 131,167

7 Claims. (Cl. 229—52)

This invention relates to a shipping container and carrier.

An object of the invention is to provide a device of this kind which is equally useful for both 5 of the purposes indicated.

Another object of the invention is the provision of such a device adapted to be formed of a single blank of material.

Another object is the formation of a device of 10 this kind in which integral handle means may be formed, the handle having the advantages of unusual strength and of comfort to the user.

Another object is to provide a shipping container formed of a single blank having interlocking parts, and which said parts are protected 15 from direct pressure by the contents of the container.

Another object is to provide a container and carrier of the character indicated, adapted for 20 efficiency and simplicity both in manufacture and in use.

These and other objects are attained by the 25 means described herein and illustrated in the accompanying drawing in which Figure 1 is a plan view of the blank formed in accordance with the present invention.

Figure 2 is a cross-sectional view of the erected 30 container conditioned likewise for use as a carrier.

Figure 3 is a side elevational view of the device 35 as seen in Figure 2.

Various types of carriers and of containers 40 have heretofore been used but so far an effective device adapted for both of these uses and equally efficient for both, has not been developed. One 45 of the disadvantages in this type of device has been that the container did not effectively and safely retain the contents in position. Another disadvantage has been that the carrying means provided have been weak and likewise uncomfortable to the hand.

These and similar disadvantages in pre-existing 50 structures are obviated by the means of this invention.

With reference to the drawing, the present 55 device contemplates the use of a blank 5 preferably formed of flexible material such as card board. The body of the blank may be rectangular and elongated as shown and at one end be provided with a pair of laterally projecting flaps 6 and 7. Adjacent these flaps a pair of ears 8 and 9 is formed. Corresponding ears 10 and 11 project laterally of the blank adjacent the opposite end of the latter. The extreme opposite 60 end of the blank constitutes a flange 12.

The blank is provided, adjacent its ends, with transverse score lines 13 and 14 and three central score lines 15, 16 and 17. Between the latter, two top sections 22 and 23 are disposed.

The container is erected into operative position 5 by attaching together, as suggested at 18 (Figure 2), the flange 12 and the opposite end portion 19 of the blank, whereby a bottom for the container is formed. The blank is now further bent upon the score lines 13 and 14 for forming 10 the substantially parallel side walls 20 and 21. A top for the container is provided by the portions of the blank between the central score 15 lines 15 and 17. In the conditions of the container as it is used for shipping purposes, the top is unbent and substantially parallel to the bottom of the container, that is, the two sections 22 and 23, lie in a common plane.

The ends of the container are formed by the flaps and ears previously mentioned. The flaps 20 6 and 7 are turned upwardly of the section 19 and the ears 8—9 and 10—11, respectively, are interlocked across the bottom of the container, in a manner well known. The interlocking of the ears is indicated in dotted lines in Figure 2. In 25 this position the interlocked ears enclose the flaps 6 and 7. It will be seen in Figure 2 that the ends thus provided on the container extend only part way to the top of the container. It will further be seen that the flaps 6 and 7 extend upwardly within the container to a substantial 30 height. As shown in Figure 2, said flaps are illustrated as extending to a height somewhat less than that of the interlocking ears but nevertheless of such height as to project above the interlocking portions of the ears, which portions are indicated in dotted lines. The latter characteristic is valuable for relieving pressure from the interior of the container upon said interlocked 35 portions so that the latter do not tend to come 40 apart during use of the container either as a shipping medium or as a carrier, as will be later described.

It is to be noted that the device as thus far 45 described is particularly well adapted for shipping purposes, due to its durable construction and likewise because, due to its square shape, it permits of efficient and stable stacking of the filled containers for shipment.

The use of the container as a carrier will now 50 be described. The top sections 22 and 23 are each provided with a finger aperture 24 and 25 formed by striking out the tabs 26 and 27 from said top sections. Said tabs are, however, 55

hingedly connected with the associated apertures as at 28 and 29. When it is desired to modify the container for use as a carrier, the top of the container is bent up into arched formation along its central score line 16, this movement being made possible due to the fact that the upper portions of the side walls 20 and 21, above the ears and flaps formed at the ends of the container, may be flexed toward one another as shown in Figure 2. A handle for carrying the container may now be formed by pushing inwardly the tabs 26 and 27 into the overlying relationship seen in Figure 2. It will be seen that the cross-sectional outline of the grip formed by said tabs and the portions of the sections 22 and 23 which lie between the finger apertures, is triangular and rounded at the corners, making for strength, and comfort to the hand.

The carton itself is adapted to be placed in a flat collapsed position for shipment and storage. For this purpose, the flaps and ears forming the ends of the carton are left unbent and disposed in the same plane as the body of the carton, which may be doubled upon itself along the score line 16. The attachment of the flange 12 to the bottom section 19, is, of course, made permanent at the time of manufacturing the container of this invention.

What is claimed is:

30. 1. A shipping container and carrier comprising a flexible blank having two opposite end portions attached together for constituting a bottom, the blank being formed to provide two side walls and a top, a flap at each end of said bottom and projecting upwardly therefrom, and a pair of interlocking ears at each end of the side walls and adapted to enclose said flaps, said top being scored longitudinally along the middle and the halves thereof provided with aligned finger apertures, said top being adapted to be bent up along its score line into arched formation whereby said apertures are brought into opposed relation to form a carrying handle.

45. 2. A shipping container and carrier comprising a bottom, a pair of opposed side walls, a top, a flap at each end of said bottom and projecting upwardly therefrom, and a pair of interlocking ears at each end of the said walls and adapted to enclose said flaps, said top being scored longitudinally along the middle and the halves thereof being provided with aligned finger apertures, the top being adapted to be bent up along its score line into arched formation whereby said apertures are brought into angular relation to form a carrying handle.

50. 3. A shipping container and carrier comprising a bottom, a pair of opposed side walls substantially parallel throughout, a top, and ends extending only part way to the top, said top being provided on opposite sides of the middle with a pair of aligned finger apertures, and the side walls, in the portion thereof above said ends, being adapted to be flexed toward one another to provide for arching of the top whereby said fin-

ger apertures are brought into opposed relation for forming a handle.

4. A shipping container and carrier formed of flexible material and comprising a bottom, a pair of opposed side walls, a top, and ends extending only part way to the top, said top being scored along a median line and the halves thereof provided with aligned finger apertures, the top being adapted to be bent up along its score line into arched formation whereby said apertures are brought into angular opposed relation to form a carrying handle.

5. A shipping container and carrier formed of flexible material and comprising a bottom, a pair of opposed side walls, a top, and ends projecting upwardly from said bottom and extending only part way to the top, said top being scored longitudinally along the middle and the halves thereof provided with aligned finger apertures, and a tab hingedly associated with and normally disposed in each aperture, said top being adapted to be bent up along its score line into arched formation whereby said apertures are brought into opposed relation to form a handle, and said tabs being adapted to be pushed in and disposed in overlying relationship for providing, with that part of said top disposed between said apertures, a grip of substantially rounded triangular cross-section.

6. A shipping container and carrier formed of flexible material and comprising a bottom, a pair of opposed side walls, and a top, said top being scored longitudinally along the middle and the halves thereof provided with aligned finger apertures, and a tab hingedly associated with and normally disposed in each aperture, said top being adapted to be bent up along its score line into arched formation whereby said apertures are brought into opposed relation to form a handle, and said tabs being adapted to be pushed in and disposed in overlying relationship for providing, with that part of said top disposed between said apertures, a grip for carrying the container.

7. A shipping container and carrier consisting of a blank of flexible material having two opposite end portions attached together for forming a bottom, the blank being suitably scored to provide for formation of a pair of opposed side walls and a top, a flap at each end of said bottom and adapted to project upwardly therefrom, a pair of interlocking ears at each end of the side walls and adapted to enclose said flaps, said ears and flaps extending only part way to the top, said top being scored longitudinally along the middle and the halves thereof provided with aligned finger apertures, and a tab hingedly associated with and normally disposed in each aperture, said top being adapted to be bent up along its score line into arched formation whereby said apertures are brought into opposed relation to form of said top a convenient handle, and said tabs being adapted to be pushed in and disposed in overlying relationship to provide a handle grip.
